UNITED STATES PATENT OFFICE.

ROYAL R. MILLER, OF CHICAGO, ILLINOIS, ASSIGNOR TO ADOLPH KARPEN, OF CHICAGO, ILLINOIS.

REVOLVING-SEAT DAVENPORT.

1,143,848.

Specification of Letters Patent. Patented June 22, 1915.

Application filed September 23, 1912. Serial No. 721,811.

To all whom it may concern:

Be it known that I, ROYAL R. MILLER, a citizen of the United States, and a resident of the city of Chicago, in the county of Cook and State of Illinois, have invented certain new and useful Improvements in Revolving-Seat Davenports; and I do hereby declare that the following is a full, clear, and exact description of the same, reference being had 10 to the accompanying drawings, and to the numbers of reference marked thereon, which form a part of this specification.

In revolving seat davenports as heretofore constructed some difficulty has been experienced in pivotally supporting the davenport seat upon the davenport frame in such manner as to insure ease of action in opening and closing the davenport, and also to afford such outward displacement of the 20 davenport seat and the mattress frame supported thereon to permit the same to clear the back of the davenport or other portions of the frame. Furthermore, in such davenports heretofore the opening of the davenport to extend the mattress frame has resulted in the elevation of the mattress frame above the normal level of the seat when closed, and in many instances connection of the seat frame with the davenport frame has 25 been so insecure that such structures have frequently proven unreliable and unsatisfactory.

The object of this invention is to so construct a revolving seat davenport that the 35 bed or mattress frame thereof shall be supported when extended at substantially the same level as the davenport seat when the device is closed.

It is also an object of the invention to afford 40 a construction whereby the operation of opening or extending the davenport acts to move the seat and the parts supported thereon outwardly to a sufficient extent to afford ample clearance from the back of the 45 davenport.

It is an object of the invention to afford a construction wherein the pivotal connection between the davenport seat and the davenport frame is exceedingly strong and durable, and whereby the davenport seat with 50 the mattress frame and bedding supported thereon is firmly supported in the davenport seat when closed, and whereby the inverted davenport seat affords a very rigid

support for the inner half of the mattress 55 frame when the device is extended.

It is an object of the invention to afford interlocking cam and pivot plates arranged in pairs at each end of the seat frame and davenport frame, and so constructed as to 60 interlock at all times in either of the adjusted positions of the device, to afford a rigid support, and serving also as a cam to adjust the seat with the load supported thereon outwardly or inwardly of the frame, 65 as the device is opened or closed.

It is an object of the invention to afford an exceedingly strong, simple and durable device of the class described, consisting of 70 few parts, and those so related as to render the device simple and certain in operation, and not likely to get out of order.

The invention in a preferred form is illustrated in the drawings, and is hereinafter more fully described.

As shown in the drawings: Figure 1 is an 75 end elevation of a device embodying my invention, with the end of the davenport frame removed. Fig. 2 is a similar view showing the device opened. Fig. 3 is a top plan view 80 of the same. Fig. 4 is a bottom plan view of the mattress frame. Fig. 5 is an enlarged view in elevation of the cam and pivot plates, showing the same at normal position. Fig. 6 is a similar view illustrating the relative 85 position of said plates when the seat has been rotated about forty-five degrees from the normal position, in opening. Fig. 7 is a similar view, illustrating the position the plates assume when the seat is revolved past 90 center in opening. Fig. 8 is a similar view illustrating the position and mutual engagement of the plates when the davenport is fully opened. Fig. 9 is an enlarged end elevation of the inner cam and pivot plate, 95 that is secured to the davenport seat. Fig. 10 is a similar view of the stationary cam and pivot plate, that is secured to the end of the davenport frame. Fig. 11 is an enlarged 100 fragmentary view illustrating the means for elevating and supporting the inner mattress frame section upon the davenport seat when open. Fig. 12 is a section taken on line 12-12 of Fig. 2 and illustrates a convenient locking mechanism adapted for use in connection with my invention. Fig. 13 is an enlarged section on line 13-13 of Fig. 2, but with the davenport in folded position.

Fig. 14 is an enlarged section on line 14—14 of Fig. 12, but with the davenport in folded position. Fig. 15 is an enlarged inner face view illustrating the articulation of the mattress frame sections together on the middle section thereof, at one end of the same and with the brace rod omitted.

As shown in the drawings: 1 indicates the end frame members and 2 the back frame of 10 a davenport having pivotally mounted therein a davenport seat 3, upon which is supported the sectional mattress frame foldable to contain the bedding therein, and revoluble with said seat in opening and in closing the 15 davenport. As shown, the seat frame 4 is constructed of structural metal, for example, of angle bar, to afford a rectangular frame having the flanges directed upwardly and the webs directed inwardly at the bottom of 20 the frame, afforded thereby, and having a resilient mattress fabric 5 connected on said webs to support the upholstery of the seat, which fits into the seat frame thus formed and beneath which may be provided springs 25 of any suitable kind if desired. Extending from each front corner of said mattress frame is an angle bar leg 6, which extends to near the lower end of the front leg 7 of the davenport, and on which, substantially 30 filling the space between the front leg 7 and the davenport frame, is a front or cover board 8 affording the front finish and concealing the mattress frame and bedding when the davenport is closed, as shown in Fig. 1. 35 Extending downwardly from the seat frame from the rear side thereof near each corner are short angle bar hangers 9, and secured within and between the hangers 9 and front legs 6 of the seat frame is a sub-frame 10, 40 also constructed of angle bar, parallel with the seat frame and spaced slightly below the same. Rigidly secured on the end at the outer side of the sub-frame near the middle thereof is a cam and pivot plate 11, 45 said cam and pivot plate 11 is riveted along its upper edge to the end member of the sub-frame, as shown in Fig. 1, and projects well below the same. Secured in said cam and pivot plate near the rear end and on the 50 inner side thereof is a cylindric pin 12 having an enlarged head 13 thereon, and, as shown, at its forward end said cam and pivot plate is extended to near the front edge of the davenport seat and is there provided with a downwardly facing shoulder 55 14 which lies substantially in alinement with the middle of said plate. As shown also a slot A is provided in said cam and pivot plate, which extends from near the pivot pin 12 horizontally and forwardly to near the middle of said plate, and then is directed 60 downwardly to near the lower edge of the plate, as shown more plainly in Figs. 1, and 5 to 8 inclusive. An intersecting slot 65 communicates in the slot A near the rear end

thereof, and inclines upwardly and forwardly to near the upper edge of said plate, and above the downwardly directed portion of said slot A and at its extremity is directed slightly forwardly to afford a rear forwardly directed shoulder or detent 15 projecting thereinto. Rigidly secured upon each end 1 of the davenport frame, to correspond in position with the pivot and cam plate 11 on the sub-frame 10 is a locking plate 16 75 which is provided with a straight horizontal slot B extending longitudinally therein near its middle and from near the rear end of said plate to near the front end thereof, and, as shown, the upper wall of which is cut away near the middle to afford a short interval of greater width in said slot. The pivot pin 12 on the pivot and cam plate 11 extends into and fits in said slot with the head 13 thereof lying outside the same and in a suitable recess or groove in the end frame to permit free travel of said pin in said slot, as shown in Figs. 5 to 8 inclusive and in Fig. 13. A pin 17 is rigidly secured on the inner side of said locking plate at a point 80 therein to extend into the upper end of the inclined slot in said plate when the pivot pin 12 is at the rear end of the slot B in said locking plate, as shown in Fig. 5. As shown also an upwardly directed, inwardly sprung 85 tongue 18 is provided integral with the forward end of the locking plate at a point to afford at its bottom a shoulder 19 to receive the shoulder 14 of the pivot and cam plate when the seat of the davenport is supported in normal position, as indicated in Figs. 1, 5 and 13. Rigidly secured on the rear side of the sub-frame at each corner thereof is a rearwardly and downwardly projecting 90 bracket arm 20, and connecting the same and journaled at its ends in said brackets is a downwardly bent or sprung bar 21 which may be tubular if desired, and which is substantially straight for the greater part of its length, the ends only bending upwardly and then outwardly to engage said brackets, and being of a sufficient length to carry the major portion of said bar downwardly to, and, if preferred, into the seat frame as shown 95 in Fig. 2. Journaled on the ends of said brace bar adjacent each of said brackets 20, by means of a suitable apertured leg 22 extending downwardly on the under side thereof from near its middle is a short mattress frame section 23 constructed of angle bar. Articulated with the ends of said short mattress frame section 23 are the end rails 24 of the inner mattress frame section which, together with the inner side rails 25 thereof, 100 are also constructed of angle bar rigidly engaged together at the angles. An outer folding mattress frame section constructed similarly with the inner mattress frame section is articulated at the ends of its end members 26, with the outer ends of said short sections. 105

A short folding leg 27 is pivotally engaged at the outer side of each of the end frame members 24 of the inner mattress frame section, with the upper end thereof 5 extending somewhat above the mattress frame, and of a length below its pivot on the mattress frame to bear upon the sub-frame as shown in Fig. 11 to support the inner mattress frame section at operative 10 position when the davenport is extended. A bar 28 is pivotally connected with the upper end of said leg 27 and with the short section 23 of the mattress frame, as shown in Fig. 11, so that in opening and closing 15 the davenport said leg is automatically extended to or retracted from supporting position. In a similar manner a leg 29 is pivotally engaged at each end of the outer or folding mattress frame section, and extends 20 above the same, and is of a length to support the same in normal operative position and a bar 30 similar to the bar 28 is engaged on the short section 23 of the mattress frame and with the upper end of said 25 leg to swing the same automatically as above described in opening or closing the davenport.

The operation is as follows: When the davenport is closed, as shown in Fig. 1, the 30 mattress frame is folded beneath and supported on the seat, and the pivot cam plate and the locking plate are in mutual engagement, as shown in Fig. 5, that is to say, the pivot pin 12 is at the extreme rear end of 35 the slot B in the locking plate and the shoulder 14 of the pivot cam plate bears upon the shoulder 19 of the locking plate. Said cam and pivot plate is thus firmly engaged and supported on the locking plate and between 40 said plate and the tongue 18. In this position the seat is in normal position and the pin 17 projecting into the inclined slot in the plate 11 is firmly engaged by the detent 15 in said slot, with any forward movement 45 of the seat. When the seat is inverted as shown in Fig. 2 the pivot cam plate and the locking plate are in the relation indicated in Fig. 8, and a lock is provided to prevent the downward swing of the middle of the 50 mattress frame by the weight applied thereon. Said lock rigidly engages the inverted seat from movement when the davenport is open, thereby maintaining the mattress frame in a horizontal plane. For this purpose a bolt 32 is slidably engaged through 55 the flange on each of the front seat legs or brackets 6, and adapted to project into a suitable recess therefor in a plate 31 secured on the end of the davenport frame at the inner side thereof. Said bolt may be actuated in any suitable manner. As shown however a bell crank 33 is pivotally supported 60 on the front board 8 at the inner side thereof, and one arm of the bell crank pivotally engages the inner end of the bolt 65

and the other end thereof is adapted for manual engagement for actuation as shown in Fig. 12.

In opening the davenport the seat is rotated upwardly and inwardly, pivoting or rotating upon the pivot pin 12, the pin 17 serving as a fulcrum to move the pivot pin along the slot B in the locking plate as indicated in Figs. 6 and 7, and eventually entering the downwardly curved portion of 70 the slot A, as shown in Fig. 7, and thereby moving the seat somewhat forward until the pivot pin is at the forward end of the slot B and the pin 17 is at the inner end of said curved slot. When inverted the upper or folding section of the mattress frame may be engaged and sprung outwardly and downwardly, utilizing the short section 23 of the mattress frame as a lever to elevate the inner section, while the relative movements of the mattress frame section actuate 80 said legs 27 and 29 through the connections afforded by the links or bars 28 and 30. 85

From the construction described it is obvious that an effective lock for the seat is 90 afforded in each of its adjusted positions and that a relatively large space is afforded for bedding within the folded mattress frame when the device is closed. Of course the mattress frame may be provided with any 95 desired number of folding sections, dependent upon whether a long or a short davenport frame be employed, and if desired other or supplemental locks may be employed.

In the construction illustrated in Fig. 4, 100 I have shown a wood frame comprising end members 34 and a back member 35 and the front board 8, which are secured to inclose the seat frame and to which the upholstery may be tacked or otherwise secured if preferred.

Details of the construction may of course be varied. I have shown a preferred form of my invention, and I do not propose limiting the patent therefor otherwise than as 110 necessitated by the prior art.

I claim as my invention:

1. In a revolving seat davenport a davenport frame having end members thereon and a transverse locking plate rigidly secured on each end member in a vertical plane, and having a horizontal slot therein, a pin rigidly secured on each locking plate above the middle of said slot, and an inwardly projecting offset at the forward end 115 of each locking plate affording an upwardly facing shoulder. 120

2. A revolving seat davenport, the davenport frame having end members thereon of transversely extending parallel locking plates, one secured on the inner side of each of said end frame members, and having an elongated horizontal slot therein, an inwardly projecting pin secured on each locking plate above the middle of said slot, an 125 130

inwardly offset, upwardly projecting tongue at the forward end of each locking plate affording an upwardly facing shoulder at its throat, the revolving seat, a pivot and 5 cam plate secured on each end thereof, a headed pivot pin secured therein, and engaging in the slot in the locking plate, and a forwardly directed arm on said plate adapted to engage between the hook and 10 locking plate to support the seat at normal position, said pivot plate having a diagonal slot therein to receive the pin on the locking plate.

3. In a revolving seat davenport a combination with the ends of the davenport frame and the revolving seat of a locking plate secured on one of the same and having a horizontal slot therein, a locking pin secured in 15 said plate above the slot, a pivot pin on the other plate adapted to engage in said slot, a 20 V-shaped slot in said plate having its apex directed toward the pivot pin, and the ends of said slot directed obliquely toward opposite edges of the plate to receive the locking 25 pin therein, an offset hook on one of said plates adapted to engage over the other to lock said plate from further movement at one of its normal positions.

4. In a revolving seat davenport the davenport frame and the revoluble seat therein, a pivot and locking plate affording the connection between the same and adapted for engagement respectively thereto, and the one having a longitudinal slot therein, a 35 locking pin secured therein adjacent the middle of the slot, the other having a rearwardly directed V-shaped slot therein, one end of said slot inclining obliquely upward above the middle of the plate, the other end 40 of said slot extending horizontally, then downwardly below the middle of said plate, a pivot pin rigidly secured near the rear end of said plate, the pins on the respective plates slidably engaging each in the 45 slot in the other, and acting to move the seat bodily on said pivot pin when the seat is rotated, and interlocking projections on the forward ends of said plates acting to rigidly support the same when the seat is at normal.

5. In a revolving seat davenport the davenport frame, the revolving seat frame pivotally supported thereon, the extendible mattress frame carried on the seat, a swinging leg on the mattress frame adapted to 55 rest on the inverted seat frame to support the mattress frame, and mutually engaging locking and pivot plates secured respectively to the davenport frame and seat ends and acting to positively interlock to support the seat at either of its adjusted positions, and mutually engaging means on 60 said plates acting to shift the seat bodily while revolving the same to or from its adjusted positions.

6. In a device of the class described a

davenport frame, a revoluble seat frame, companion plates secured on each and affording connection between said frames, and an offset lug on one and a tongue on the other to engage the same to lock said frames 70 when in normal position.

7. In a device of the class described a plurality of mattress frame sections, supporting legs pivoted on the inner and outer terminal sections, and actuating means therefor pivoted on the common intermediate 75 section.

8. In a device of the class described a revoluble seat frame, a plurality of articulated mattress frame sections, and a plurality of 80 legs therefor adapted to slide on said frame and bear thereon to support one of said sections.

9. In a device of the class described the combination of a davenport frame, a seat 85 frame resting on a floor revoluble therein, companion plates affording connection therebetween, a sectional mattress frame comprising terminal sections joined together, and positively actuated legs adapted to support said inner and outer sections, the former adapted to slide and bear upon the seat frame, and the latter upon said floor.

10. In a device of the class described a 95 mattress frame comprising inner and outer terminals sections, a common intermediate section connecting said terminals sections, legs pivotally connected on said terminal sections respectively to support the same, 100 and links connected with each of said legs and with said common intermediate sections to actuate said legs.

11. In a device of the class described a davenport frame, a seat frame mounted 105 therein, companion plates secured on said davenport and seat frame respectively to permit said seat frame to be revolved and inverted while supported in said davenport frame, a foldable sectional mattress frame 110 connected on the underside of said seat frame, a sub-frame mounted on the underside of said seat frame, pivotally actuated legs for supporting said mattress frame when the same is extended for use, certain of said 115 legs adapted to rest upon the floor, and the other of said legs adapted to rest perpendicularly upon said sub-frame of the seat frame.

12. In a device of the class described a 120 davenport frame, a seat frame mounted therein, a sub-frame mounted on the underside of said seat frame, companion plates secured upon the davenport frame, companion plates secured on said sub-frame of 125 said seat frame permitting said seat frame to be moved into an inverted position while supported in said davenport frame, brackets secured on said sub-frame, a foldable sectional mattress frame, the intermediate sec- 130

tions thereof supported upon said brackets, and positively actuated legs on the inner and outer sections of said foldable mattress frame, the former of said legs adapted when 5 the mattress frame is extended to rest upon the sub-frame of said seat frame and the latter of said legs adapted to rest upon the floor to support the mattress frame.

13. In a device of the class described a 10 davenport frame, a seat frame, companion plates secured upon the davenport frame, a sub-frame on said seat frame, companion plates secured upon said sub-frame, a foldable sectional mattress frame mounted on 15 the underside of said seat frame, comprising inner and outer sections, an intermediate section connecting the two, a bracket on said sub-frame supporting said intermediate section, legs on said inner and outer mattress 20 frame sections respectively, connections between said legs and the intermediate section of the mattress frame to cause said legs to be positively actuated into supporting position when the mattress frame is extended, 25 the leg on said inner section when extended into supporting position resting perpendicularly upon said sub-frame and the leg of the outer section adapted to rest upon the floor.

14. In a device of the class described a 30 davenport frame, a seat frame mounted therein, companion plates secured upon said davenport frame, a sub-frame mounted on said seat frame, companion plates secured upon said sub-frame adapted to coact with 35 the companion plates on said davenport frame to permit said seat frame to be inverted in the davenport frame, a foldable sectional mattress frame mounted upon the underside of said seat frame, comprising 40 inner and outer mattress frame sections, an intermediate section connecting the two, a bracket secured to said sub-frame and pivotally supporting said intermediate section,

the corresponding intermediate sections at each end of the mattress frame positively 45 and rigidly connected to insure simultaneous movement thereof when the mattress frame is extended or folded, supporting legs on said respective inner and outer mattress frame sections, and links connected to said 50 legs and to said intermediate sections at each end of the mattress frame to positively move said legs into supporting position when the mattress frame is extended.

15. In a device of the class described a 55 davenport frame, a seat frame mounted therein, companion plates secured upon said davenport frame, companion plates to coact therewith secured upon said seat frame, means on said respective companion plates 60 to guide the same during relative movement therebetween to insure proper movement of said seat frame, means on the edges of said respective companion plates adapted to coact to limit the movement of said seat frame, 65 a mattress frame comprising a plurality of pivotally connected sections mounted on the underside of said seat frame, and adapted to be extended when said seat frame is inverted in the davenport frame, a positively actuated 70 leg on each of the outer mattress frame sections adapted to rest on the floor to support the same when the mattress frame is extended for use, and a positively actuated leg on each of said inner mattress frame sections 75 adapted to support the same upon said inverted seat frame when the mattress frame is extended for use.

In testimony whereof I have hereunto subscribed my name in the presence of two sub- 80 scribing witnesses.

ROYAL R. MILLER.
